UNITED STATES PATENT OFFICE.

JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

TELEPHONE-AMPLIFIER.

1,185,878.

Specification of Letters Patent.

Patented June 6, 1916.

Application filed May 6, 1912. Serial No. 695,334.

To all whom it may concern:

Be it known that I, JOHN J. COMER, a citizen of the United States of America, and resident of Chicago, Cook county, Illinois, 5 have invented a certain new and useful Improvement in Telephone-Amplifiers, of which the following is a specification.

My invention relates to telephone amplifiers or repeaters—that is, to instruments 10 which are employed for repeating voice-current impulses.

My invention is particularly adapted for instruments for use in transmitting music, and in this connection is used more particularly to increase the number of instruments which are operated by a single master transmitter, rather than increasing the amplitude of the vibrations, such as is the case when the instrument is employed as a repeater. It 20 will be obvious, however, that if desired the instrument could be adjusted so as to operate as a repeater.

In the transmission of music it is important that the instrument be so constructed 25 that all extraneous or foreign vibrations are eliminated. In this connection it is desirable that the microphone transmitter be very flexibly connected with the magnetic receiver and, furthermore, that all metallic connections between the vibrating armature 30 and the parts of the microphone transmitter be eliminated. If this is not done certain metallic and other objectionable sounds are obtained. Furthermore, in order to obtain 35 the most perfect reproduction of musical sounds it is necessary that the vibrating parts be very accurately adjusted and be so constructed that they are capable of vibrating very rapidly, and yet they must be 40 controlled in order that the vibrations received will be accurately transmitted.

The principal objects of my invention are the provision of an amplifier which is so constructed that efficient results are obtained 45 in the manner pointed out above. That is, I provide an amplifier in which the armature is so constructed and mounted that it is very sensitive to the variations of current in the electromagnet of the receiver, 50 but the vibrations of this armature are con-

trolled so as to prevent any false vibrations occurring in the same. Furthermore, the microphone part of my amplifier is entirely free from any metallic connection with the vibrating armature and is very flexibly connected with the same. 55

By the use of my amplifier I am enabled to energize as many as five hundred reproducers from a single master transmitter.

The features and objects of my invention 60 will be more readily understood by reference to the accompanying drawings, in which—

Figure 1 is a side view of an amplifier embodying the features of my invention. Fig. 2 is a top view of the same. Fig. 3 65 is an end view. Fig. 4 is an end view taken on the line 4—4 of Fig. 2, with the microphones and mounting plates removed. Fig. 5 is a sectional view taken on line 5—5 of Fig. 2. Fig. 6 is a sectional view taken on 70 line 6—6 of Fig. 2.

Throughout the drawings similar reference characters refer to similar parts.

I have illustrated an amplifier comprising a U-shaped magnet 7 having pole-pieces 8 75 and 9. On the pole-piece 9 is mounted an electromagnet coil 10. A pair of non-magnetic supporting arms or brackets 11 and 12 are mounted on the forward ends of these pole-pieces, and these supporting arms are 80 joined together by a pair of non-magnetic cross-bars 13 and 14. Mounted on each of these cross-bars 13 and 14 there is a pair of threaded supporting posts 15 and 16 upon the upper ends of which are mounted the 85 flat springs 17 and 18. These flat springs extend beneath and are secured to the aluminum bar 19 which supports the armature 20. This armature is preferably rectangular in shape and is supported adjacent to the two 90 pole-pieces 8 and 9, thereby forming a double air gap in the magnetic circuit. The use of this double air gap produces a much more sensitive armature and one which will respond more readily to the rapid changes 95 of current in the coil 10.

Mounted upon the end of the supporting arms 11 and 12 there is a supporting plate 21. The base plate 22 is mounted adjacent to the supporting plate 21 and is separated 100

therefrom by the felt packing 23. These two plates are preferably recessed as shown, whereby this felt packing is more readily held in place. Mounted on the base plate 22 5 is a pair of microphones each comprising stationary electrodes 24 and 25 and a movable electrode 26. These movable electrodes are carried by stems 27 which pass through the plates 21 and 22 and are secured to opposite ends of the aluminum bar 19. These rods 27 do not contact with the plates 21 10 and 22 and are insulated from the bar 19 by means of the rubber washers 28 and the felt packing 29. These stationary electrodes 24 and 25 are separated by the insulating rings 30 which form the carbon receptacle 31 within which is located the granular carbon. These rings 30 are separated by 15 means of washers 32^a surrounding the tie-bolts 34. The space between these rings is then packed with asbestos. This asbestos likewise surrounds the stems 27 and also the periphery of the movable electrode 26. Upon the opposite sides of each of these 20 microphones there is mounted a non-magnetic supporting plate 33, and the various parts of the microphone transmitter are all held together by the tie-bolts 34. The base plate 22 and the plate 21 are connected together by means of the tie-bolts 34, which tie-bolts are thoroughly insulated from the base plate 22 by means of the felt packing 36 which surrounds each of the tie-bolts and sets within recesses in this base plate, as 25 clearly shown in Fig. 2. Passing through the central portion of the plate 21 there is a threaded stud 37 which is provided with an enlarged end portion 38 which bears against a felt disk 39 set within the recessed portion of the bar 19.

By means of the construction described the armature is properly adjusted with respect to the pole-pieces, and when so adjusted the springs 17 and 18 are preferably 40 slightly bowed downward. The tension of these springs is sufficient to prevent the armature coming in contact with the pole-pieces when attracted to the same, and the vibrations of this armature are controlled 45 and damped by means of a felt disk 59 bearing against the enlarged end portion 38 of the stud 37. It will further be noticed that the entire weight of this armature and the supporting parts are carried by the lower part of the supporting arms 11 and 12. I find that this gives much better results than when this armature is supported 50 from above by means of the plate 21, as in the latter instance the vibrations of the armature are apt to set up foreign vibrations in this plate which would be more apt to be transmitted to the microphones than in the present construction, in which very few

of these foreign vibrations are set up in this plate 21.

65

In the operation, the vibrations of the armature are transmitted through the bar 19 to the rods 27 and thus operate the movable electrodes of the microphones in a manner which will be readily understood. This vibration of the armature would tend to set up foreign or extraneous vibrations in the frame of the magnet, and this would be transmitted through the supporting arms 11 and 12 to the plate 21. By the use of the 70 felt packing 23 located between this plate 21 and the supporting plate 22, however, I prevent any of these extraneous vibrations from being transmitted to the microphone. This felt packing is preferably quite loose, 75 so that a very flexible construction is obtained, but by having these plates recessed in the manner shown and described the parts are firmly held in position. It will, of course, be understood that in place of felt 80 I could employ other insulating material, such as rubber or leather, but I find that the best results are obtained by the use of felt. By this construction, therefore, it will be seen that I provide an armature which is 85 very sensitive and which responds readily to the slight changes in current in the magnet coil, and, furthermore, by having all parts insulated all extraneous vibrations are prevented from affecting the microphones. I 90 thus obtain very efficient transmission and one which is particularly advantageous in the transmission of musical sounds.

95

While I have illustrated one particular embodiment of my invention, it will be understood that I do not wish to be limited to the exact construction shown and described.

100

What I claim as my invention is:—

1. In a telephone amplifier, an electromagnet, an armature therefor, a member directly supporting said armature, a rod connected at one end to said member and insulated from all metallic contact therewith, and a microphone transmitter having a movable electrode connected directly to the opposite end of said rod.

105

2. In a telephone amplifier, a magnet, an armature therefor, a supporting member for said armature, rods connected to the opposite ends of said supporting member and insulated therefrom, and microphone transmitters having independent movable electrodes connected to the opposite ends of said rods.

110

3. In a telephone amplifier, an electromagnet, an armature therefor, a supporting plate carried by said magnet, a base plate mounted adjacent to but insulated from said supporting plate, a microphone transmitter mounted on said base plate, and a connecting rod connected at one end to an electrode of

115

120

125

said transmitter and at its opposite end connected to but insulated from said armature.

4. In a telephone amplifier, an electromagnet, an armature therefor, a supporting plate carried by said magnet, a base plate mounted adjacent to said supporting plate, a felt disk separating said plates, a microphone transmitter mounted upon said base plate and having a movable electrode, and 10 connections from said movable electrode to said armature.

5. In a telephone amplifier, an electromagnet, an armature therefor, a supporting member for said armature, a supporting plate carried by said magnet, a base plate mounted adjacent to said supporting plate, a felt disk located between said plates, a pair of microphone transmitters each having a movable electrode mounted upon said base 20 plate, and connections from said movable electrodes to opposite ends of said supporting member.

6. In a telephone amplifier, an electromagnet, an armature therefor, a supporting member for said armature, a supporting plate carried by said magnet, a base plate mounted adjacent to said supporting plate, a felt disk located between said plates, a pair of microphone transmitters each having a 30 movable electrode mounted upon said base plate, and connections from said movable electrodes to opposite ends of said supporting member, said connections being insulated from said supporting member.

35 7. In a telephone amplifier, an electromagnet, a pair of non-magnetic supporting arms mounted upon the pole-pieces of said magnet, a supporting member carried by said arms, an armature mounted upon said 40 supporting member, a supporting plate mounted upon said arms, a base plate mounted adjacent to said supporting plate and insulated therefrom, a microphone transmitter mounted upon said base plate, 45 and connections from said transmitter to said armature.

8. In a telephone amplifier, an electromagnet, a pair of non-magnetic supporting arms mounted upon the pole-pieces of said 50 magnet, a supporting member carried by said arms, an armature mounted upon said supporting member, a supporting plate mounted upon said arms, a base plate mounted adjacent to said supporting plate and insulated therefrom, a pair of microphone transmitters having movable electrodes, and connecting rods connected to said 55 movable electrodes and connected to but insulated from said supporting member.

60 9. In a telephone amplifier, a U-shaped electromagnet, a pair of supporting arms carried by said magnet, a supporting plate carried by said arms and extending across

the end of said magnet, an armature for said magnet, and means carried by said plate for 65 damping the vibrations of said armature.

10. In a telephone amplifier, a magnet, non-magnetic supporting arms carried by said magnet, an armature carried by said supporting arms, and a soft pad mounted 70 adjacent to said armature for damping the vibrations of said armature.

11. In a telephone amplifier, a magnet, a pair of non-magnetic supporting arms carried by said magnet, a pair of flat springs 75 carried by said supporting arms, a supporting member carried by said springs, and an armature mounted upon said supporting member.

12. In a telephone amplifier, an electro- 80 magnet, a pair of supporting arms carried thereby, a pair of flat springs adjustably carried by said supporting arms, a supporting member mounted transversely on said springs, an armature carried by said member, and means located adjacent to said armature for damping the vibrations of the same.

13. In a telephone amplifier, a magnet, a pair of supporting arms, a pair of springs 90 carried by said supporting arms, an armature carried by said springs, a supporting plate mounted on said supporting arms, and an adjustable member carried by said plate for damping the vibrations of said armature.

14. In a telephone amplifier, a pair of supporting arms, a pair of flat springs adjustably carried by said supporting arms, a supporting member carried by said springs, an armature mounted upon said member, a supporting plate mounted on said supporting arms, a base plate mounted adjacent to said supporting plate but insulated therefrom, a microphone transmitter mounted upon said 100 base plate, and connections from the movable electrode of said transmitter to said supporting member.

15. In a telephone amplifier, a pair of supporting arms, a pair of flat springs adjust- 110 ably carried by said supporting arms, a supporting member carried by said springs, an armature mounted upon said member, a supporting plate mounted on said supporting arms, a base plate mounted adjacent to said 115 supporting plate but insulated therefrom, a microphone transmitter mounted upon said base plate, connections from the movable electrode of said transmitter to said supporting member, and means carried by said supporting plate for damping the vibrations of 120 said armature.

16. In a telephone amplifier, an electro- magnet having an armature providing a magnetic circuit open at two points, means 125 including a felt disk bearing against one side

of said armature for damping the vibrations of the same, a microphone transmitter, and a rod connected directly to said transmitter and extending to said armature.

5 17. In a telephone amplifier, an electromagnet, an armature therefor providing a magnetic circuit open at two points, a pair of bowed springs for supporting said armature, means for damping the vibrations of

said armature, a microphone transmitter, 10 and connections from said armature to said transmitter.

Signed by me at Chicago, Cook county, Illinois, this 3rd day of May, 1912.

JOHN J. COMER.
